UNITED STATES PATENT OFFICE.

JOHN GWOZDZIEWICZ AND MAJK BIZON, OF BRETZ, WEST VIRGINIA.

LANTERN.

1,115,067.

Specification of Letters Patent.

Patented Oct. 27, 1914.

Application filed July 24, 1914. Serial No. 852,891.

To all whom it may concern:

Be it known that we, JOHN GWOZDZIEWICZ and MAJK BIZON, subjects of the Emperor of Austria-Hungary, residing at Bretz, in the county of Preston and State of West Virginia, have invented certain new and useful Improvements in Lanterns, of which the following is a specification.

This invention relates to new and useful improvements in lanterns.

The primary object of this invention is to provide an adequate top and bottom ventilating means for the burner chamber of a lantern.

15 A further object is to provide a four-sided glass lantern with a hollow dome-shaped ventilating cover, and especially adapted for carrying a candle and provided with a screened ventilated bottom.

20 With these general objects in view, and others that will appear as the nature of the invention is better understood, the same consists in the novel combination and arrangement of parts hereinafter fully described, 25 illustrated in the accompanying drawing, and pointed out in the appended claims.

In the drawings forming a part of this application, and in which like designating characters refer to corresponding parts

30 throughout the several views—

Figure 1 is a longitudinal vertical central sectional view taken through the device. Fig. 2 is a perspective view of the top reflecting plate removed, and, Fig. 3 is a perspective view of the bottom ventilating plate detached.

40 Referring more in detail to the drawing, the invention is illustrated in connection with a four-sided lantern consisting of glass sides 10 positioned within the framework 11, and having a top 12 provided with outlet perforations 13, and with a bottom 14 having air inlet openings 15. A tubular holder 16 is mounted within the device upon the bottom 14 and substantially centrally thereof, and adapted to receive a candle 17 removably mounted therein. The top 12 supports a smoke-bell 18 centrally positioned therebeneath and in direct vertical alignment above the candle 17. Protecting wires 19 are arranged around the frame exten-

55 riorly of the glass side while a bail 19 is hinged to the top 12 adapted as a handle for carrying the lantern. Beneath the bottom 14 a box-shaped metallic casing 20 is secured, being provided with perforations 21 through its bottom and sides and has its open top positioned beneath the openings 15 of the lantern bottom, while corner supporting legs 22 are secured to the lower surface 60 of the said bottom. A hollow cover 23 is hinged as at 24 to the top 12 and is provided with a central exit opening 25 for the products of combustion, which latter enter within the chamber 26 of the cover through 65 the top perforations 13. Within the chamber 26 a baffle plate 27 is secured to the upper face of the top and has semi-circular curved sides 28, having perforations 29 therethrough, and extending directly above 70 the perforations 13. A door for the lantern is preferably provided by hinging one of the sides as at 30.

75 While the forms of the invention herein shown and described are what are believed to be preferable embodiments thereof, changes may be made in the device without departing from the spirit and scope of the appended claims.

What we claim is:—

80 1. A device of the class described comprising a combination with a lantern having a candle mounted therein, and with a perforated top and bottom, of a smoke bell centrally positioned on the under surface of 85 said top, a hinged hollow cover upon said top and having a central outlet opening, a baffle plate within said cover, having perforated curved flanges extending over the perforations of said top, and having their 90 side edges spaced from said top, the said plate being attached to the top, at a point between said perforations and beneath the cover opening.

95 2. A device of the class described comprising a lantern top and bottom having perforations therethrough, a box-shaped casing having perforated bottom and walls, and secured beneath the lantern bottom and the perforations thereof, a dome-shaped cover 100 hinged to the lantern top, and forming a chamber therein, and having a central out-

let for the products of combustion, a baffle plate within said chamber secured to the lantern top beneath said cover opening, and having side curved perforated flanges terminating in spaced relations with respect to said top, and positioned above the perforations of said top.

In testimony whereof we affix our signatures in presence of two witnesses.

JOHN GWOZDZIEWICZ.
MAJK BIZON.
